JOHN W. BEAN, OF HENRY, ILLINOIS.

Letters Patent No. 74,880, dated February 25, 1868.

IMPROVED APPARATUS FOR BENDING METALLIC PLATES.

The Schedule referred to in these Letters Patent and making part of the same.

TO ALL WHOM IT MAY CONCERN:

Be it known that I, JOHN W. BEAN, of Henry, in the county of Marshall, and State of Illinois, have invented certain new and useful Improvements in the Bending and Hardening of Metal Plates; and I do hereby declare that the following is a full, clear, and exact description thereof, reference being had to the accompanying drawings making part of this specification, and to the letters of reference marked thereon, like letters indicating like parts wherever they occur.

To enable others skilled in the art to construct and use my invention, I will proceed to describe it.

My invention consists in an improvement in the construction of plates for bending and holding plough-plates while being tempered, and an arrangement of levers and devices for operating the same to bend the plates, as hereinafter described.

Figure 1 is a perspective view, and

Figure 2 a transverse vertical section of the improved device used in my process.

It is customary, in making the mould-boards for steel ploughs and cultivators, to first cut the plates of the required form, then press or bend them into the required form, after which they are hardened by the usual process. It is necessary that these plates shall be precisely alike in form, in order to fit the frames or standards to which they are bolted, and which, in the case of ploughs, are usually made of cast iron, and being rigid will not yield. It is found in practice that when the hot plates are immersed in water or other liquid, for the purpose of hardening them, they are apt to spring more or less, and thus get out of shape; and as it is desirable to make them very hard, in order to wear well, any subsequent attempt to change their form by springing or bending them is very apt to crack or break them. To remedy these difficulties, and insure the bending of the plates to the exact form required, and keep them so while being hardened, is the object of my invention.

To accomplish this, I make a clamp, consisting of two plates, A and E, corresponding in form to the shape of the article when finished, which in this case is supposed to be a mould-board for a plough. These plates may be hinged together on their rear edge, as shown at f, and provided with handles C B, as represented. On their inner surfaces these plates are provided with a series of ribs or projections, e, as shown, with spaces between them. The plate, after being heated, is placed between the plates A E, which are then shut together, as shown in fig. 2, and thereby of course bending the plate e, which lies between them, to the required form. The plate thus bent or formed is then taken out and heated to the proper degree, when it is again placed in the mould or clamps, and the whole together is then plunged into the cooling-liquid. The plate e, resting on the ribs e, is held firmly in place, while the liquid flows readily and freely between the ribs, thus coming at once in contact with the surfaces of the plate, and thereby cooling and hardening the same, without springing or warping it in the least. In this manner I am enabled to produce any number of plates of perfect uniformity.

In making mould-boards and cultivator-teeth or shovels, I mount the clamp on a low table, I, having a block, D, for it to rest on, and hook the rear side fast by means of a rod, o, while the upper plate may be drawn down by a lever, II, and rod l, as shown in fig. 2.

It is obvious, however, that the devices may be varied to suit the circumstances of the case, and according to the article to be made. In bending and hardening large plates for other purposes, it may be necessary to have the dies or clamps secured in and operated by a power-press, and to have it so arranged that the whole may be lowered into a suitable tank, by means of pulleys, and swung around by a crank; but these are details not necessary to be herein described, as the person using my invention will of course arrange them as he may deem best.

I am aware that frames consisting of independent bars, united at their ends like a gridiron, have heretofore been used for holding plates while being inserted in a tempering-bath, and such I do not claim; but having thus described my invention,

What I claim, is—

The improved apparatus for bending and tempering plough and similar plates, when constructed and arranged in its several parts substantially as described.
